ATTORNEY

UNITED STATES PATENT OFFICE

103,530

DESIGN FOR A UNIFORM CAP OR SIMILAR ARTICLE

Jacob Foster, New York, N. Y.

Application August 31, 1936, Serial No. 64,655

Term of patent 14 years

To all whom it may concern:

Be it known that Jacob Foster, a citizen of the Union of Soviet Socialist Republics and resident of New York city, in the county of Bronx and State of New York, has invented a new, original, and ornamental Design for a Uniform Cap or Similar Article, of which the following is a specification, reference being had to the accompanying drawing forming part thereof, in which,

I claim:

The ornamental design for a uniform cap or similar article, as shown.

JACOB FOSTER.
